[57] **CLAIM**

The ornamental design for an articulated arm with internal feed and edge guide for a paint roller unit, as shown and described.

DESCRIPTION

FIG. 1 is a perspective view of the articulated arm with internal feed and edge guide for a paint roller unit of the present invention shown with a paint roller assembly for use therewith in phantom.

FIG. 2 is a front view thereof;

FIG. 3 is a rear view thereof;

FIG. 4 is a left side view thereof;

FIG. 5 is a right view thereof;

FIG. 6 is a top view thereof; and,

FIG. 7 is a bottom view thereof.

The broken lines are for illustrative purposes only and form no part of the claimed design.
